UNITED STATES PATENT OFFICE.

RILEY L. DAVIS, OF MOORESVILLE, NORTH CAROLINA.

ELEVATOR.

SPECIFICATION forming part of Letters Patent No. 292,995, dated February 5, 1884.

Application filed November 20, 1883. (No model.)

To all whom it may concern:

Be it known that I, RILEY L. DAVIS, of Mooresville, in the county of Iredell and State of North Carolina, have invented a new and useful Improvement in Elevators, of which the following is a full, clear, and exact description, reference being had to the annexed drawings, forming part of this specification.

This invention relates to the class of elevators and adjustable scaffolds which are constructed according to the lazy-tongs principle; and the invention consists of the novel arrangement and combination of parts herein-after set forth and claimed.

15 In the drawings, Figures 1 and 2 are side elevations of my improved elevator, taken from sides at right angles to each other; and Figs. 3 and 4 are detail views.

A B C D indicate four pairs of lazy-tongs arranged in the form of a quadrilateral prism, with the knees or joints *a* of each pair connected to the knees or joints *a* of the two pairs adjacent thereto. These connections are made by forming the pivot *b* of one knee or joint 25 with a flange or flanges, *c*, at one end, which serve as a bearing for a pivot, *b'*, of another knee or joint. Inside the extensible prism thus formed is arranged a fifth pair of lazy-tongs, *E*, which is set parallel with two of the pairs above described, and has its knees or joints *a* connected to the pivots *b*, located in the longitudinal axis of the two other pairs of the four forming the prism. The pivots *b* are likewise formed with flanges *c* at one end, between which the knees *a* of the pair *E* are pivoted. This fifth pair of lazy-tongs is provided 35 with two series of continuous toggle-braces, *F*, arranged on opposite sides thereof, with alternate knees *e*, connected to the pivots *d'*, located in the longitudinal axis of the tongs *E*, and the intermediate knees, *e'*, connected to the pivots *d*, located in the longitudinal axis of the two pairs of tongs parallel with the tongs *E*. The pivots *d'* and *d* are also to be formed 45 with flanges *c*, for supporting the pivots of the knees *e* and *e'*.

Instead of the toggle-braces *F*, two chains may be used, being extended and attached in the same manner as the bars. The chains being positively connected to the tongs *E* and to the two tongs of the prism which are parallel 50 with *E*, will tighten and brace the device when

the latter is extended. The tongs *E* and the toggle-braces *F* are made to extend both above and below the prism formed by the tongs A B 55 C D, and at their upper ends are connected to a cross-rod, *H*, which is adapted to move in vertically-slotted pendants *I* on the platform *J*. A threaded rod, *K*, is connected to this cross-rod and extended vertically upward 60 through the center of the platform.

In the upper side of the platform is loosely fitted a nut or sleeve, *L*, which is provided with a bevel-gear, *M*, adapted to be operated by another bevel-gear, *N*, supported in a standard, *O*, and having a crank, *P*, and which nut screws on the rod *K*. When the nut is rotated by the bevel-gears, the rod *K* is made to rise or sink through a perforation in the platform, the nut being supported by its 70 connection to the latter, and the movement of the rod *H* thus produced causes the tongs *E* to extend or collapse, and by their connection with the braces and other tongs a like movement is communicated to the latter. The lower end of the tongs *E* is pivoted in a base, *Q*, and is provided with vertically-slotted guides *R*, in which moves a cross-rod, *S*, connected to the tongs *E*. The guides *R* are supported by the base *Q*. 75

With the above construction the central tongs, *E*, serve to work the elevator, the other tongs and the braces serving to give strength and steadiness to the structure.

The tongs *E* may be made of iron to increase 85 the strength, while the other parts may be made of wood.

Instead of the screw-rod *K*, for operating the tongs *E*, the power may be applied at the base in any well-known manner. 90

What I claim is—

1. The combination, with a pair of lazy-tongs, of a number of additional pairs of lazy-tongs having their knees connected in a flexible manner to the knees of the former, or to 95 the knees of the former and to each other, substantially as shown and described.

2. The combination, with a pair of lazy-tongs, of four additional pairs of lazy-tongs arranged in the form of a quadrilateral prism 100 around the former, and having their pivotal points connected in a flexible manner to the pivotal points of the former and to each other, and the two series of continuous toggle-braces

connected to the longitudinally-central pivots of the main or central and two of the side lazy-tongs, substantially as shown and described.

3. The combination, with the series of 5 flexibly-connected lazy-tongs, of a platform supported on top of the central pair of lazy-tongs, and having slotted pendant-guides, a cross-rod connecting opposite joints of the said central pair and adapted to slide in said 10 slotted guides, a screw-rod connected to said

cross-rod and extending up through the platform, a nut screwing on said screw-rod and supported by the platform, and means for rotating the nut, substantially as shown and described.

RILEY L. DAVIS.
